UNITED STATES PATENT OFFICE

2,432,733

LIFTING MECHANISM FOR SLIDING
CAR DOORS

Frank Ditchfield, Cleveland, Ohio, assignor to
The Youngstown Steel Door Company, Cleve-
land, Ohio, a corporation of Ohio

Application March 7, 1945, Serial No. 581,480

8 Claims. (Cl. 16—99)

1

This invention relates to lifting mechanism for sliding car doors.

It is an object of this invention to provide lifting mechanism for sliding car doors which shall lie within the most critical tunnel clearance diagram and afford ample working clearances between the several parts of the mechanism.

A further object is to provide lifting mechanism for sliding car doors which shall obtain a reduction in the number of parts heretofore required.

A further object is to provide lifting mechanism for sliding car doors which shall eliminate all castings.

A further object is to provide lifting mechanism for sliding car doors which shall be simple and sturdy in construction and secure a reduction in cost.

A further object is to provide lifting mechanism for sliding car doors which shall embody connecting arms so constructed as to provide trunnions for the mechanism.

A further object is to provide lifting mechanism for sliding car doors which shall embody connecting arms so constructed as to provide trunnions for the mechanism and receive the pins for the roller of the lift mechanism.

Other objects of the invention will become clear as the description thereof proceeds.

In the drawings forming part of this specification:

Fig. 1 is a fragmentary elevation with parts broken away of a sliding car door equipped with lifting mechanism embodying the instant invention.

Fig. 2 is a vertical section taken on line 2—2 of Fig. 1.

Fig. 3 is a horizontal section taken on line 3—3 of Fig. 1.

Referring to the drawings the numeral 10 designates a sliding door for railway house cars. The door is of known construction and briefly may be described as embodying a metallic panel 11 formed with horizontal corrugations, one of which is indicated at 12. At the vertical margins the metallic panel is offset outwardly as indicated at 13 and 14 and is secured as by means of rivets 15 and 16 to vertical reinforcing members indicated generally by the reference numerals 17 and 18.

The lower marginal portion of the metallic panel is offset outwardly as indicated at 19 so as to provide a vertical depending portion 20 which is secured to the upstanding flange 21 of a Z-shaped reinforcing member 22. A metallic backing plate 23 is secured to the panel 11 above the outwardly offset portion 19 and to the depending flange 24 of the Z-shaped reinforcing member 22. The outwardly offset portion of the panel 11, the backing plate 23 and the Z-shaped reinforcing member 22 cooperate to provide a box section 25

2

within which the lifting mechanism embodying the instant invention is housed.

The upper portion of the door is substantially similar to the upper portion of the door illustrated and described in applicant's co-pending application, Serial No. 465,233, filed November 11, 1942.

The lifting mechanism embodies a plurality of spaced rollers 26—26 which are adapted to support the door for movement upon a track 27 supported by means of a plurality of brackets one of which is shown partially at 28 upon the underframe 29 of the car. The rollers engage the track through openings 30 formed in the web of the bottom Z-shaped reinforcing member 22.

Each of the rollers is mounted upon a pin 31 which extends eccentrically from and is integral with an outer trunnion 32. Each of the trunnions 32 is journalled in the door and for this purpose a bearing 33 is provided. The lower half of the bearing 33 is formed in the upstanding flange of the Z-shaped door reinforcing member 22 and the upper half of the bearing 33 is formed in a plate 34 which is disposed above and lies in the same plane as the flange 21 of the Z-shaped member, as more clearly appears from Figs. 1 and 2 of the drawings. The plate 34 may, if desired, be welded to the flange 21.

30 A connecting arm 35 is mounted upon each of the roller pins 31 and is constrained to rotate with said pin as by means of splines 36. Each connecting arm 35 is extended in the form of an integral boss 37 which is hollow, as shown in Figs. 2 and 3 of the drawings, and through which the roller pin 31 extends eccentrically. Each of the bosses 37 serves as an inner trunnion for the lifting mechanism and for this purpose is journalled in a bearing 38 formed in the web 39 of a channel shaped member 40. The legs 41 and 42 of the channel shaped member are flanged outwardly as indicated at 43 and 44. The flanges 43 and 44 bear against the inner face of the upstanding flange 21 and the bearing plate 34 and are secured thereto as by means of rivets 45 and 46.

Each of the pins 31 is retained against outward movement relative to the door and for this purpose the inner ends of the pins are preferably peened over as indicated at 47.

The left-hand outer trunnion 32 is formed with flat faces 48 and 49. A lever 50 formed with similar internal faces is mounted upon said trunnion and is retained upon the door and guided in its movement by means of a quadrant 51 secured to the door and a Z-shaped clip 52 fastened to the inner face of the lever in the manner more clearly illustrated in Figs. 1 and 2 of the drawings.

60 The lever 50 is utilized to operate the lifting

mechanism and in order to insure uniform lifting of the door the arms 35 are connected by means of a bar 53 shown in the form of a pipe having flattened ends through which lugs 54 integral with the arms 35 extend. Disengagement of the connecting bar from the lugs 54 is prevented by means of cotter pins 55 which extend through the lugs.

In order to lift the door and support it for easy movement upon the rollers 26-26 the operating lever 50 is moved in clockwise direction. Movement of rotation is thereby imparted to the outer trunnion 32 and through the pin 31 to the inner trunnion 37. In view of the fact that the pin 31 is eccentric to the trunnions 32 and 37 a lifting force is imparted to the door thereby raising it above the track 27 upon which it is normally frictionally supported and supporting it upon the rollers 26-26 for movement along the track.

It is apparent from the foregoing invention that castings heretofore utilized in lifting mechanisms of the type involved have been eliminated. It will also be apparent that the roller housings also heretofore used have been eliminated and that in addition to the savings effected thereby the depth of the lifting mechanism has been substantially decreased without the sacrifice of the clearance between the several parts of the lifting mechanism. The instant mechanism therefore aids in reducing the overall width between the doors on opposite sides of the cars and thereby makes it possible to provide lifting mechanism which satisfies the most critical tunnel clearance diagram.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. Lifting mechanism for sliding car doors comprising a plurality of integral eccentrically related trunnion and pin members, rollers mounted upon said pins, connecting arms, said arms embodying integral hollow trunnions, said pins extending into said hollow trunnions in eccentric relationship therewith, means constraining said pins to rotate with said latter trunnions, means on the inside of a said door connecting said arms for simultaneous movement, and a lever mounted upon a trunnion of one of said integral trunnion and pin members.

2. Lifting mechanism for sliding car doors comprising a plurality of eccentrically united trunnion and pin members, rollers mounted upon said pins, connecting arms, hollow trunnions on said arms, said pins extending into said hollow trunnions in eccentric relationship therewith, means constraining said pins to rotate with said latter trunnions, means on the inside of a said door connecting said arms for simultaneous movement, and a lever mounted upon one of said trunnions.

3. Lifting mechanism for sliding car doors comprising a plurality of trunnions, pins of smaller diameter than said trunnions extending eccentrically from said trunnions and rotatable therewith, rollers mounted on said pins, connecting arms, hollow trunnions on said arms, said pins extending into said hollow trunnions in eccentric relationship therewith, means constraining said pins to rotate with said latter trunnions.

nions, means connecting said arms for simultaneous movement, and a lever mounted upon one of said trunnions.

4. Lifting mechanism for sliding car doors comprising a plurality of trunnions, pins integral with and of smaller diameter than said trunnions extending eccentrically therefrom, rollers mounted on said pins, connecting arms, integral hollow trunnions on said arms, said pins extending into said hollow trunnions in eccentric relationship therewith, means constraining said pins to rotate with said latter trunnions, means connecting said arms for simultaneous movement, and means for imparting rotation to one of said trunnions.

5. Lifting mechanism for sliding car doors comprising a plurality of trunnions adapted to be journaled in a said door, pins extending eccentrically from and rotatable with said trunnions, rollers mounted on said pins, connecting arms adapted to be journaled in said door, said arms being eccentrically mounted upon said pins for rotation therewith, means connecting said arms for simultaneous movement and a lever mounted on one of said trunnions said rollers, pins and connecting arms lying on the same side of said door.

6. Lifting mechanism for sliding car doors comprising a plurality of trunnions, pins extending eccentrically from and rotatable with said trunnions, rollers mounted on said pins, connecting arms, trunnions on said arms, said pins extending into said arms in eccentric relationship with said arm trunnions, means constraining said pins to rotate with said arms, means connecting said arms for simultaneous movement, and a lever mounted on one of said trunnions.

7. Lifting mechanism for sliding car doors comprising a plurality of trunnions, pins of smaller diameter than said trunnions extending eccentrically therefrom and rotatable therewith, rollers having an internal diameter smaller than the diameter of said trunnions mounted upon said pins, connecting arms, trunnions on said arms, said pins being connected to said arms for rotation therewith in eccentric relationship with said arm trunnions, said arms extending beyond the periphery of said rollers, means connecting said arms for simultaneous movement, and a lever mounted on one of said trunnions.

8. In a sliding lift door having a box section at the lower edge thereof embodying transversely spaced walls, a plurality of trunnions journaled in one of said walls, a plurality of connecting arms disposed between said walls formed with trunnions journaled in the other of said walls, pins extending between and rotatable with said first mentioned trunnions and said arms, said pins being eccentric relative to said first mentioned trunnions and said arm trunnions, rollers mounted on said pins, means connecting said arms for simultaneous movement, and a lever mounted on one of said trunnions on the outside of said door.
